(57) **CLAIM**

The ornamental design for the floating game table, as shown and described.

DESCRIPTION

FIG. 1 is a perspective view of a floating game table showing an embodiment of the design in an environment of use within a pool and supporting various food and beverage articles;

FIG. 2 is a top perspective view of the floating game table of FIG. 1;

FIG. 3 is a top plan view of the floating game table of FIG. 1;

FIG. 4 is a bottom plan view of the floating game table of FIG. 1;

FIG. 5 is a left side elevation view of the floating game table of FIG. 1;

FIG. 6 is a right side elevation view of the floating game table of FIG. 1;

FIG. 7 is a rear end elevation view of the floating game table of FIG. 1; and,

FIG. 8 is a front end elevation view of the floating game table of FIG. 1.

The broken lines showing a portion of a pool and food and beverage articles are provided for the purpose of illustrating environmental structure and form no part of the claimed design.

1 Claim, 6 Drawing Sheets
